(57) CLAIM

The ornamental design for an outdoor lighting fixture, as shown and described.

DESCRIPTION

FIG. 1 is a front elevational view of an outdoor lighting fixture according to my new design.

FIG. 2 is a top plan view thereof.

FIG. 3 is a right side elevational view thereof.

FIG. 4 is a left side elevational view thereof.

FIG. 5 is a rear elevational view thereof.

FIG. 6 is a bottom plan view thereof.

FIG. 7 is a perspective view thereof as seen from above; and,

FIG. 8 is a perspective view thereof as seen from below.

The broken lines shown on the drawings depict portions of the outdoor lighting fixture that form no part of the claimed design.
